COLLAPSIBLE WINDER SHAFT

Frank E. Langdon, Vancouver, Wash.

Application June 6, 1932, Serial No. 615,669

4 Claims. (Cl. 242—72)

This invention relates generally to the paper-making industry, and particularly to a collapsible shaft on which paper is wound after being manufactured.

The main object of this invention is the production of an improved form of winding shaft of the type disclosed in my former patents, Numbers 1,631,538 and 1,811,237.

The second object is to so construct the collapsible portions of the shaft that they will be supported transversely across the width thereof instead of only along the center line, as was the case in the patents above referred to.

The third object is the construction of a shaft of the type referred to in which the problems of manufacture and upkeep are reduced to a minimum.

The fourth object is the production of a collapsible winder shaft capable of withstanding severe abuse without being rendered inoperative.

These, and other objects, will become more apparent from the specification following as illustrated in the accompanying drawing, in which:

Fig. 1 is a longitudinal section taken through the operating end of the shaft showing same in an expanded position, the view being taken along the line 1—1 in Fig. 4.

Fig. 2 is a longitudinal section similar to Fig. 1 but showing the opposite end of the shaft also in an expanded position.

Fig. 3 is a longitudinal section of the complete shaft with the mid portion broken away and taken in a plane normal to the section shown in Figs. 1 and 2 showing the jaws of the shaft in contracted position.

Fig. 4 is a transverse section along the line 4—4 in Fig. 1.

Fig. 5 is a transverse section along the line 5—5 in Fig. 3.

Fig. 6 is an enlarged end elevation of one of the holding rivets.

Fig. 7 is a section showing the holding rivet in side elevation.

Fig. 8 is a section taken through the central portion of one end of the device along the line 8—8 in Fig. 3.

Similar numbers of reference refer to similar parts throughout the several views.

Referring in detail to the drawing, there is shown a central sleeve 10 made of heavy tubing material having turned in the surface thereof a plurality of grooves 11 whose sides 12 are square and whose sides 13 are bevelled (as shown).

Through the sleeve and intersecting each groove 11 is a keyhole slot 14 having an enlarged end 15.

In one end of the sleeve 10 is inserted a solid extension 16 having its intermediate portion 17 reduced in diameter, as shown. The extension 16 has an enlarged bevelled flange 17a formed thereon which matches with a corresponding flange 18 on the sleeve 10, thereby forming a V groove for holding purposes, the welding metal 19 being shown.

The member 16 has projecting therefrom a cylindrical portion 20 which is provided with three equi-distant grooves 21 which are in alignment with the slots 14. Through the portion 20 is formed a tapering recess 22 one side of which has a notch 23 formed therein for the reception of the point 24 of an operating bar 25. The end 26 is provided with an internal thread to receive the threaded portion 27 of a plug 28 provided with a head 29 which may be flattened or provided with holes 30 for a spanner wrench. From the head 29 projects a reduced shaft portion 31 similar to a portion 32 which projects from the cylindrical portion 20.

The shaft portions 31 and 32 may journal in suitable bearings which form a part of the paper machine, or may constitute a means for handling the shaft alone or with the paper wound thereon. The plug 28 is held against rotation by means of a pin 33 which itself is retained by means of a tapering sleeve 34 whose square end 35 abuts against the head 29.

On the end 20 is slidably mounted a tube 36 having an opening 37 formed in one side thereof through which the bar 25 may be inserted. The tube 36 is provided with a reduced portion 38 which equals the outside diameter of the flange 17a. The reduced portion 38 is also provided with holes 39 which are in alignment with the three grooves 21.

Surrounding the sleeve 10 are three arcuate jaws 40 which, when extended in the form shown in Fig. 4, have their outer surfaces 41 lying within a complete circle constituting the interior of a roll of paper 42. Each jaw 40 is provided with a plurality of transverse ribs 43 along the length thereof. Each rib 43 has one edge 44 bevelled to correspond with the side 13 of the groove 11. Each rib 43 is secured to the inner side of its jaw 40 by means of the rivets 45 and also by the reduced portion 46 of the rivet 47 whose cylindrical head 48 is provided with a flattened portion 49 forming a T head whose under side 50 is curled to correspond with the inner surface 51 of the sleeve 10.

It can be seen that by flattening the sides 49 the wearing surfaces of the rivet 47 are greatly in-

creased and the tendency of the rivets to rotate is correspondingly decreased, in fact eliminated altogether.

The rivets 47 are secured in place on their respective jaws 40 and the heads 48 are permitted to pass through the enlarged ends 15 of the key-hole slots 14 and the entire jaw is then removed so as to bring the flattened surfaces 49 within the slot portions 14. Each jaw 40 is then secured 10 longitudinally to the tube 36 by means of its own pin 52 which is welded in place. Each pin 52 passes through its respective hole 39 into the groove 21. The purpose of the groove 21 is to hold the parts in proper alignment.

15 Within the sleeve 10 is placed a tension spring 53 one end of which is attached by an eye bolt 54 to a washer 55 by means of a nut 56. The washer 55 is limited in its rotation by means of a pin 57 for which the rivet heads 48 form stops. 20 The opposite end of the spring 53 is connected by an eye bolt 58 to a washer 59. A nut 60 is placed on the end of the bolt 58 outside of the washer 59. The washer 59 engages the ends 61 of the screws 62 which extend through the sides of the sleeve 25 10 into the interior thereof. The nut 60 may be prevented from rotating unless driven by an ordinary lock washer or by inserting a pin 63 in the washer 59 and allowing its head to project in the direction of the nut 60, which nut is suitably 30 recessed to receive the projecting pin end 63. This is a common expedient and of course will prevent the nut 60 from rotating, unless being turned with sufficient force to lift the pin 63 out of the nut recess against the tension of the spring 53.

35 The operation of this form of the device is identical with those described in my former patents and consists briefly of the following. When the shaft is empty it is merely placed in position on the paper machine and the paper 40 started to wind thereon. It will be observed that the spring 53 has previously forced the jaws 40 in the direction of the sleeve 34, causing each jaw to move outwardly along its full length and to be supported transversely across its entire width. 45 When the paper 42 is wound upon the roll to an extent at which it is desirable to remove same therefrom it is only necessary to insert the bar 25 and exert a pull which will move the tube 36 in the direction of the shaft end 32, drawing all of 50 the jaws 40 with it by reason of the pins 52 which attach the jaws to the tube 36 permitting the jaws to contract, due to the fact that the ribs 43 are now in register with the grooves 11.

55 While I have illustrated and described my improved form of winding shaft as having a groove turned in the arbor or sleeve 10, it is obvious that the same results may be obtained by utilizing a tubular sleeve whose outside diameter approximates the present diameter at the bottom of the groove and adding thereto a hardened band whose outside diameter would approximate the present outside tube diameter.

I claim:

60 1. A collapsible winder shaft having a central tubular sleeve containing a plurality of grooves formed around same along the length thereof, the corresponding edges of all of said grooves forming inclines with relation to the surface of the

sleeve, a plurality of transversely curved longitudinal jaws constituting a covering for said sleeve, each of said jaw members having secured thereto a plurality of arcuate ribs substantially the full width of the inner side of the jaw and adapted to be slidably brought into register with said grooves for the purpose of collapsing said shaft or to ride upon the outer cylindrical surface of said sleeve for the purpose of holding said shaft in an expanded position, one edge of each rib being beveled to conform with the groove incline, the cylindrical inner surface of each rib resting upon the cylindrical outer surface of the central sleeve when the shaft is in the expanded position.

65 2. A winder shaft as described in claim 1, together with a spring for urging said ribs out of said grooves into an expanded position, said shaft having an opening wherein may be inserted a lever opposed to said spring by means of which said ribs may be moved to and held in a contracted position within said grooves.

70 3. A collapsible winder shaft comprising a central tubular sleeve having a series of encircling grooves formed around same along the length thereof, the corresponding edge of each groove 100 sloping with relation to the axis of the sleeve, said sleeve having three longitudinally straight but transversely arcuate jaws substantially encircling said sleeve, a plurality of arcuate ribs surrounding said sleeve, each rib being fastened to a 105 jaw and occupying one of said grooves when the shaft is contracted, said sleeve having longitudinal keyhole slots formed therein, each jaw member having a T-head rivet projecting from its inner side through one of said keyhole slots, said 110 rivet having the sides of its head flattened and slidably occupying the narrow portion of the keyhole slot, a plug threaded into one end of said sleeve having a shaft extension formed thereon, a cylindrical member secured within the opposite end of said sleeve also having a shaft extension formed thereon, a tube slidably mounted on said cylindrical extension, said tube and cylindrical extension having registering openings formed therein, means for attaching each of said 115 jaws to said tube in a manner to permit radial movement of said jaws, and spring means for urging all of said ribs in a direction which will cause said ribs to move out of said grooves onto the cylindrical outer surface of the sleeve.

75 4. A collapsible winder shaft having a tubular inner sleeve forming an arbor and characterized by having circumferential grooves formed along the length thereof, one corresponding edge of all of said grooves inclining with relation to the axis of the sleeve, three separate transversely arcuate jaws enclosing said tube along its entire length, each of said jaws having inner ribs secured thereto each of which extends transversely of the jaw and adapted to register with the respective sleeve grooves for the purpose of permitting the attached jaw to move radially toward the axis of the sleeve, a spring for urging all of said jaws in a direction which will cause said ribs to ride up the inclined edges of the grooves onto the outer cylindrical 140 circumference of the sleeve for the purpose of locking the jaws in an expanded position.

FRANK E. LANGDON.
